KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

INERTIA-ACTUATED WEFT DETECTOR ON A TRANSFERRER ARM.

Application filed November 10, 1927. Serial No. 232,434

This invention relates to improvements in weft detectors mounted on regularly moving transerrer arms and it is the general object of the invention to provide a detector 5 slidable on the transerrer arm and actuated by a weighted member as the transerrer arm arrives at its lowest position.

In co-pending application Ser. No. 120,490 filed by Turner there is shown a detector in the transerrer arm actuated by a weighted device the inertia of which tends to give the detector an indicating movement as the transerrer arrives in its lowest position. In another co-pending application 15 Ser. No. 232,432 filed by Cederlund there is shown a detector carrier slidable in a direction parallel to the yarn being detected so that the operation of the detector will not be interfered with by a pivotal movement 20 as has been the case heretofore when detectors of the side slipping type carried on the transerrer arm have been pivoted thereto. It is an important object of my present invention to utilize the inertia principle set 25 forth in the Turner application and the sliding detector carrier shown in the Cederlund application with the resulting easier contact between the detector teeth and the yarn. In the said Turner application the inertia 30 force is exerted in a vertical direction but when this idea is applied to a detector carrier slidable in a horizontal direction it is necessary to provide means for converting the vertical motion into a horizontal one and it 35 is a further object of my invention to accomplish this last named result.

It is a still further object of my invention to provide a single resilient means interposed between the weighted member and the latch which controls the position of the 40 indicating plunger.

With these and other objects in view which will appear as the description proceeds, my invention resides in the combination and arrangement of parts hereinafter 45 described and set forth in the claims.

In the accompanying drawings wherein one form of my invention is shown,

Fig. 1 represents a vertical section through 50 that part of the transerrer arm which ex-

tends over the bobbin, the parts being in the position they assume when sufficient weft is present,

Fig. 2 is a view similar to Fig. 1 but with the parts moved to indicating position, 55

Fig. 3 is a fragmentary top plan view taken in the direction of arrow 3, Fig. 1,

Fig. 4 is a fragmentary horizontal section on line 4—4 of Fig. 1,

Fig. 5 is a vertical section on line 5—5 of 60 Fig. 1, and

Fig. 6 is a diagrammatic view of the mounting of the transerrer arm.

Referring to the drawings the transerrer arm 10 is provided with an extension 11 65 extending normally above and parallel to the bobbin B to be detected. Said transerrer arm is given regular movements about a fixed stud S, Fig. 6, as is fully described in the patent to Ryon No. 1,372,316. The 70 extension is provided with spaced walls 12 which define a slot 13 in which the operating mechanism of the detector is located. A plunger 14 is guided so as to move in a direction substantially parallel to the bobbin B, the left end being received by a web 15 and the right end projecting beyond the body of the transerrer arm at the time of indication to cooperate with an indicating lever 16, as shown and fully described 75 in patent to Ryon No. 1,551,219.

The control for the plunger 14 includes a latch 17 pivoted on a pin 18 and having a hook 19 held by a tension spring 20 normally in notch 21 formed on the left end of 80 the plunger. A tail 22 depends from the latch and forms part of the means by which the plunger is released. A helical compression spring 23 surrounding a portion of the plunger lies between a clip 24 fast on the transerrer arm and a shoulder 25 formed on the plunger. At indication of weft exhaustion the latch is moved in a counter-clockwise direction as viewed in Fig. 1 around its stud 18 to release the plunger, 85 whereupon spring 23 moves the plunger from the non-indicating position shown in Fig. 1 to the indicating position shown in Fig. 2 when the transerrer arm is in its lowest position, so that as said arm rises it 90 95 100

will cooperate with the indicating lever 16. This releasing mechanism forms no part of my present invention and may be the same as shown in the copending application filed by Hume Patent #1,653,210.

The detecting element D has a shank 26 the lower end of which extends horizontally as at 27 and has detector teeth 27' to engage the yarn. The detector is mounted for vertical movement in a sliding carrier 28 the lower portion 29 of which is substantially horizontal and which is slidably guided by slots 30 which lie opposite each other and are formed in the walls 12. A helical compression spring 31 surrounds a portion of the detector element and is confined between shoulders 32 formed on the shank 26 and the upper horizontal portion 33 of the carrier, said spring holding the detector yieldingly in its lowest position and permitting the detector to be moved upwardly relatively to the carrier. The tail 22 of the latch extends in the path of the carrier to be moved by the latter at the time of substantial weft exhaustion. The detector element and its carrier may be substantially the same as set forth in the aforesaid copending application filed by Cederlund.

My invention relates more particularly to the means for imparting a horizontal movement to the carrier 28 through the intermediary of a weighted device and in carrying my invention into effect I extend between the walls 12 a pivot pin 40 on which is mounted for free rotation a weighted arm 41 from the lower portion of which depends finger 42 which engages the web 15 and also affords support for the right end of the tension spring 20. By this construction said spring 20 yieldingly holds the weight 41 in raised position and also yieldingly holds the latch locked. The left hand end of the arm as shown in Figs. 1 and 2 is provided with an extension 43 which may have concentric curved inner and outer surfaces 44 and 45, respectively, which are eccentric with respect to the pin 40. The extension passes slidably through an opening 46 formed in the upper horizontal portion 33 of the carrier and is proportioned to move downwardly relatively therewith.

In operation the parts are normally in the position shown in Fig. 1 with the indicating plunger in its inward or non-indicating position being retained by the latch and with the weighted arm 41 held in raised position by the spring 20 so that the carrier and the detecting element are to the left as shown in Fig. 1. On each detecting beat as the transerrer arm arrives at the bottom of its stroke the weight of the arm 41 because of the momentum thereof will tend to descend to move the carrier horizontally in the guide slots 30. This action takes place after the teeth 27' have engaged the sur-

face to be detected and when sufficient yarn is present as indicated in Fig. 1 said teeth will resist the movement of the carrier to the right in a horizontal direction under influence of the weighted arm 41. When insufficient weft is present, however, the friction between the teeth 27' and the surface being detected will have been reduced so that the weighted arm 41 and its extension 43 may move downwardly, the surface 44 moving the carrier to the right from the position shown in Fig. 1 to that shown in Fig. 2 so that said carrier engages the tail 22 to move the same in a counter-clockwise direction about its pivot to release the indicating plunger 14. The latter will thereupon move under the indication lever 16 as shown in Fig. 2 to initiate replenishment as is shown in the aforesaid patents. During the time that the weighted arm moves downwardly relatively to the transerrer arm the tension spring 20 is extended and as soon as the force of the weighted arm is spent said spring will contract to raise the weighted arm from the position shown in Fig. 2 to that shown in Fig. 1, the surface 45 under these conditions engaging the left end of the slot 46 to move the carrier to the left to restore the same to the normal position shown in Fig. 1. During the continued upward movement of the transerrer arm the plunger will be reset by mechanism not shown herein but set forth in the aforesaid Ryon Patent No. 1,551,219.

From the foregoing it will be seen that I have provided self-contained means for imparting a horizontal sliding movement to the detector and carrier by means of a downward force exerted by the weighted arm 41. It will further be seen that the spring 20 acts to raise the weighted arm to position the carrier and acts also to hold the latch in normal locking position.

Having thus described my invention it will be seen that changes and modifications may be made therein by those skilled in the art without departing from the spirit and scope of the invention and I do not wish to be limited to the details herein disclosed, but what I claim is:

1. In a weft detector for a loom having a regularly moving transerrer arm on which is mounted an indicating plunger, a movable latch normally holding the plunger in non-indicating position, a carrier slidably on the transerrer arm in a direction substantially parallel to the surface being detected, a detector mounted on the carrier, a weighted member pivoted to the transerrer arm and free to move downwardly relatively to the transerrer after the latter has reached the bottom of its stroke due to the momentum of said weighted arm, and means defining a connection between the weighted arm and the carrier whereby the downward motion

- of the weighted arm is caused to move the carrier in a substantially horizontal direction parallel to the surface being detected, said latch to be moved to plunger releasing position when the carrier moves relatively to the transferrer arm on an indicating beat of the loom.
2. In a weft detector for a loom having a regularly moving transferrer arm on which is mounted an indicating plunger, a movable latch normally holding the plunger in non-indicating position, a detector carrier movable in a substantially horizontal direction at weft exhaustion to engage the latch and said carrier being guided for sliding movement relatively to the transferrer arm, a detector mounted on the carrier, and a weighted member held yieldingly in raised position and tending to move downwardly relatively to the transferrer arm after the latter has arrived at the bottom of its stroke due to the momentum of the weighted member, said weighted member when tending to move downwardly exerting a force on the carrier tending to move the latter horizontally and in a direction substantially parallel to the surfaces being detected.
3. In a weft detector for a loom having a regularly moving transferrer arm on which is mounted an indicating plunger, a movable latch normally holding the plunger in non-indicating position, a carrier to engage the latch, a detector mounted on the carrier, means defining guides for the carrier on the transferrer arm extending in a horizontal direction and substantially parallel to the surface being detected, a weighted member pivoted on the transferrer arm and tending to move downwardly after the transferrer arm comes to rest due to the momentum of the weighted member, and an extension carried by the weighted member and having a portion to engage the carrier and tend to give the latter a horizontal motion when the weighted member moves downwardly, said member when moving under the influence of the extension of the weighted member engaging the latch to move the latter to plunger releasing position.
4. In a weft detector for a loom having a regularly moving transferrer arm on which is mounted an indicating plunger, a movable latch normally holding the plunger in non-indicating position, a carrier guided on the transferrer arm for sliding movement relatively to the transferrer arm in a direction substantially parallel to the surface being detected, a detector element mounted on the carrier, a weighted member movable relatively to the transferrer arm and tending to move downwardly after the transferrer comes to rest at the bottom of its down stroke because of the momentum of said weighted member, an extension carried by the weighted member projecting between spaced portions on the carrier, one of said portions engaging one side of the extension and cooperating with the latter to tend to move the carrier horizontally in one direction when the weighted member tends to move downwardly and the other of said portions cooperating with another part of the extension and tending to move the carrier in the opposite direction to restore the same to normal position after an indicating movement of the carrier when the weighted member moves upwardly.
5. In a weft detector for a loom having a regularly moving transferrer arm on which is mounted an indicating plunger, a movable latch normally holding the plunger in non-indicating position, a carrier guided for sliding movement relatively to the transferrer arm in a direction substantially parallel to the surface being detected, a weft detector mounted on the carrier and capable of yielding movement relatively thereto, a weighted member yieldingly held in raised position, means defining a pivotal connection between the weighted member and the transferrer arm, said weighted member tending to move downwardly around the pivotal connection after the transferrer has reached the bottom of its downward stroke due to the momentum of the weighted arm, and a curved extension rigid with the weighted arm and projecting through a slot formed in the carrier, said curved extension being formed on an arc eccentric with respect to the pivotal connection, said extension and weighted member engaging one side of the slot to move the carrier horizontally in one direction substantially parallel to the surface being detected when the weighted member moves downwardly and said extension engaging the other side of the slot to move the carrier in the opposite direction when the weighted member moves upwardly.
6. In a weft detector for a loom having a regularly moving transferrer arm on which is mounted an indicating plunger, a movable latch normally holding the plunger in non-indicating position, a detector carrier slidably mounted on the transferrer arm to move in a direction substantially parallel to the surface being detected, a detector mounted on the carrier, a weighted actuator movably mounted on the transferrer arm, operative connections between the actuator and carrier effective through the downward movement of the actuator due to its momentum to move the carrier relatively to the transferrer arm after the latter has come to rest at the bottom of its downward stroke on an indicating beat of the loom, and a single resilient means interposed between the weighted member and the latch and tending to hold the latch in normal rocking position rela-

tively to the plunger and tending also to hold the weighted member yieldingly in raised position.

7. In a weft-detector for a loom having a regularly moving transferrer arm on which is mounted an indicating plunger, a movable latch normally holding the plunger in non-indicating position, a detector carrier slidably mounted on the transferrer arm to move in a direction substantially parallel to the surface being detected, a detector mounted on the carrier, a weighted actuator movably mounted on the transferrer arm, operative connections between the actuator and carrier effective through the down-

ward movement of the actuator due to its momentum to move the carrier relatively to the transferrer arm after the latter has come to rest at the bottom of its downward stroke on an indicating beat of the loom, and a single resilient means interposed between and supported by the weighted member and the latch and tending to hold the latch in normal rocking position relatively to the plunger and tending also to hold the weighted member yieldingly in raised position.

In testimony whereof I have hereunto affixed my signature.

KENNETH J. UNWIN.
